UNITED STATES PATENT OFFICE.

ABRAHAM L. BAER, OF MILWAUKEE, WISCONSIN, ASSIGNOR OF ONE-HALF TO JOHN FALBE, OF WAUWATOSA, WISCONSIN.

PIPE.

1,148,494.

Specification of Letters Patent. Patented Aug. 3, 1915.

Application filed June 15, 1914. Serial No. 845,083.

To all whom it may concern:

Be it known that I, ABRAHAM L. BAER, a citizen of the United States, and resident of Milwaukee, in the county of Milwaukee 5 and State of Wisconsin, have invented new and useful Improvements in Pipes, of which the following is a description, reference being had to the accompanying drawings, which are a part of this specification.

10 This invention relates to improvements in pipes and more particularly to the stem portion thereof.

It is one of the objects of the present invention to provide a pipe having sectional 15 stem portions in which provision is made for effectively trapping nicotine and for trapping saliva and preventing the settlement thereof in the bowl of the pipe.

A further object of the invention is to 20 provide a pipe having means within its stem for effectively cooling the smoke drawn therethrough and thus conducing to the comfort of the user.

A further object of the invention is to 25 provide a pipe stem section which may be connected to any ordinary pipe having a removable stem and which will, when so connected, impart to the pipe the advantages before mentioned.

30 A further object of the invention is to provide a pipe which is of simple construction, is strong and durable and is well adapted for the purpose desired.

With the above and other objects in view, 35 the invention consists of the improved pipe and its parts and combinations as set forth in the claims, and all equivalents thereof.

In the accompanying drawing in which the same reference characters indicate the 40 same parts in all of the views: Figure 1 is a vertical central sectional view of a pipe embodying the improved construction; and Fig. 2 is a vertical sectional view of the improved stem section removed from the pipe 45 with the parts shown in separated positions.

Referring to the drawing the numeral 5 indicates a pipe bowl, 6 the projecting stem portion, 7 the removable stem portion and mouth piece and 8 the connecting tube for 50 removably attaching the two stem portions together. The connecting tube 8 is preferably slipped into the adjacent ends of the stem portions and frictionally holds the parts together. While this manner of connecting the stem portions together is shown

and described, it is to be understood that the parts may also be connected together in any other manner desired.

The stem portions are provided with the 60 customary bores 9 and 9'.

An inverted cup member 10 has its lower open end portion 11 removably mounted within the upper end of the connecting tube 8 and extends upwardly into the bore 9' of the removable stem. The cup member is 65 provided with an aperture 12 which opens communication between the bore 9' of the removable stem and the chamber 13 of the cup member. The cup aperture 12 is located at a point intermediate of the opposite ends of the cup member and in use the said member is positioned with the aperture extending upwardly. The open ended portion 11 of the cup member is of less 70 diameter than the remaining portion to 75 space a conical trap tube 14, extending through the open end and into the chamber, away from the side walls of the cup member. This trap tube extends to a point near the upper end of the cup tube and forms a trap 80 portion in one end of the chamber 13 between the aperture and the lower portion of the chamber to receive and hold nicotine 85 which is precipitated by the smoke passing through the trap tube and engaging and being deflected by the walls of the chamber and any foreign matter which may be carried by the smoke.

In some cases the connecting tube may be 90 formed integral with one of the stem portions or entirely eliminated when the stem is in one piece or is connected together in a manner different from that shown.

The annular space 16 surrounding the cup member and below the aperture of the cup member also serves as a trap to prevent 95 saliva from passing through the stem and into the bowl of the pipe.

When the pipe has been in use for some 100 time and it is desired to clean the same, it is only necessary to separate the parts in the manner shown in Fig. 2 and each part may then be easily cleaned.

It will be seen that the parts shown in 105 Fig. 2 may be easily inserted in any ordinary pipe having a two part stem and the pipe will then possess all of the advantageous features before described.

From the foregoing description it will 110 be seen that the smoke is caused to pass

through a circuitous passage before reaching the mouth of the user and is cooled and the nicotin and other deleterious substances are, to a large extent, removed from the 5 smoke and that the saliva is trapped in its passage toward the pipe bowl with the result that a sanitary smoke is provided for the user.

What I claim as my invention is:

- 10 1. A pipe, comprising a bowl portion provided with a stem, a cup member positioned within the bore of said stem, having its closed end located farthest from said bowl with a portion of its open end in close contact with the side-walls of said bore to serve as a closure, and provided with an aperture intermediate its length which is adapted to be positioned adjacent the upper side of said stem and beyond said closure an appreciable distance to form a saliva trap in said stem at the mouth end, and a removable trap tube open at both ends, supported solely by said cup member forming a closure for the lower end thereof and having one end extending into said cup member beyond said aperture.
- 15 2. A pipe, comprising a bowl portion pro-
- 20
- 25

vided with a stem, a cup member positioned within the bore of said stem, having its closed end located farthest from said bowl 30 with a portion of its open end in close contact with the side-walls of said bore to serve as a closure, and provided with an aperture intermediate its length which is adapted to be positioned adjacent the upper 35 side of said stem and beyond said closure an appreciable distance to form a saliva trap in said stem at the mouth end, and a removable trap tube open at both ends, supported solely by said cup member forming a closure 40 for the lower end thereof and having one end extending into said cup member beyond said aperture, the end of said trap tube nearest the bowl being of less diameter than said bore and projecting from said cup member 45 to prevent sediment from said bowl entering said cup member.

In testimony whereof, I affix my signature, in presence of two witnesses.

ABRAHAM L. BAER.
